US00D928356S

(12) **United States Design Patent** (10) **Patent No.:** **US D928,356 S**
(45) **Date of Patent:** **** Aug. 17, 2021**

(54) **LED MODULE**

(71) Applicant: **Bestco Lighting Co., Ltd.**, Zhongshan (CN)

(72) Inventor: **Zhicheng Wang**, Yunfu (CN)

(73) Assignee: **Bestco Lighting Co., Ltd.**, ZhongShan (CN)

(**) Term: **15 Years**

(21) Appl. No.: **29/703,193**

(22) Filed: **Aug. 26, 2019**

(30) **Foreign Application Priority Data**

Aug. 9, 2019 (CN) 201930432699.2

(51) **LOC (13) Cl.** **26-06**
(52) **U.S. Cl.**

USPC **D26/28**; D26/2

(58) **Field of Classification Search**

USPC D26/1, 2, 3, 14, 25, 28, 60, 72, 74, 120, D26/123, 124, 134, 135, 136, 137

(57) **CLAIM**

The ornamental design for a LED module, as shown and described.

DESCRIPTION

FIG. 1 is a perspective view of a LED module, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a circled portion IX thereof. The broken lines shown are included for the purpose of illustrating portions of the LED module which form no part of the claimed design.

1 Claim, 9 Drawing Sheets
